UNITED STATES PATENT OFFICE.

FREDERICK D. MARTIN, OF KANSAS CITY, MISSOURI.

GROMET.

1,384,565.

Specification of Letters Patent. Patented July 12, 1921.

Application filed May 5, 1920. Serial No. 379,049.

To all whom it may concern:

Be it known that I, FREDERICK D. MARTIN, a citizen of the United States, and a resident of the city of Kansas City, county 5 of Jackson, and State of Missouri, have invented certain new and useful Improvements in Gromets, of which the following is a specification.

My invention relates to new and useful 10 improvements in gromets, and has for its object the provision of a gromet having a restricted portion intermediate its ends, which will be simple in construction and economic in manufacture, and highly efficient in use.

Other objects will appear hereinafter.

The invention consists in the combinations and arrangements of parts hereinafter described and claimed.

20 The invention will be best understood by reference to the accompanying drawings forming a part of this specification, and in which,

Figure 1, is a plan view of the invention applied to a piece of fabric,

Fig. 2, is a plan view of the rear of the invention applied to a piece of fabric.

Fig. 3, is a sectional view taken on substantially line 3—3 of Fig. 1,

30 Fig. 4, is a perspective view of a portion of the invention,

Fig. 5, is another perspective view of a portion of the invention,

Fig. 6, is a plan view of the retaining plate used in the invention.

The invention comprises a pair of co-operating parts which are made substantially oval, one part 8 of which is provided with an opening formed therein, said 40 opening having an enlarged portion 9 adjacent one end of the plate 8 and a smaller portion 10 adjacent the opposite end of the plate connected by a neck 11, so that the device presents a plate 8 with an opening restricted intermediate its ends. The gromet is designed for attachment to a fabric 12, and is especially designed for use upon butchers' and bakers' aprons, and the like. With such articles of apparel, it is custom-

45 ary to have attached to the adjacent edges of the garment strings by means of which the garment may be tied upon the wearer. In removing the garments the wearer often leaves the strings in a knotted condition, so that when the garment is sent to the laundry it is necessary to unfasten the knots

before laundrying, this work resulting in a consuming of considerable time at the laundry, and adding to the expense of laundrying of the garments. Also it has been 60 found through experience, that in laundrying the strings often become detached from the garment. When a gromet of this class is used, detachable strings may be used, each having a knot formed in the opposite ends. 65 The gromets are attached to the garment at the adjacent edges with the opening 10 adjacent each other. The knotted end of the string is then inserted through the enlarged opening 13 and drawn through the neck 11 70 into the opening 10 and, the opening 10, being sufficiently small to prevent the passage of the knotted end of the string therethrough. It is evident that the removal of the strings is facilitated before the laundrying of the garments, and the liability of injuring the garments through a catching of the strings upon the article is eliminated. The plate 8 is provided with a neck 13 which projects from one side therof and which conforms in cross section to the contour of the opening formed in the plate. This neck 13 is projected through the garment and a retaining plate 75 14 having openings 9', 11' and 10' is provided, the neck 13 being thrust through the openings in said plate. After the neck 13 is projected through the fabric and the plate 14, placed thereover, the neck 13 is flattened into clinching position as shown in Fig. 3, thereby securely attaching the 80 gromet to the fabric. It has been found, from experience, that a gromet of this nature formed in the manner indicated and attached to the goods as described, suffers 85 no injury through laundrying of the garment, and is very rarely torn from the garment during the laundrying thereof.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims:—

Having described my invention, what I claim as new and desire to secure by Letters Patent is:—

1. A gromet comprising a pair of co-operating members each having an opening

therein, said opening being restricted intermediate its ends, the opening at one side of said restricted portion being larger than at the opposite side; and a neck portion projecting from one of said members, and adapted for projection through and retention in the opening in the coöperating member, substantially as described.

2. A gromet comprising a pair of coöperating members, each having an opening formed therein, said opening being restricted intermediate its ends, the opening at one side of said restricted portion being larger than at the opposite side; and a neck portion projecting from one of said members and adapted for projection through the opening in the coöperating member sufficiently to allow the clinching of said neck over said coöperating member, substantially as described.

3. A gromet comprising a pair of coöperating members each having an opening therein, said opening being restricted intermediate its ends, the opening at one side of said restricted portion being larger than at the opposite side; and a neck portion inte-

gral with and projecting from one of said members and adapted for projection through the opening in the coöperating member, said neck corresponding in cross section to the contour of said opening, substantially as described.

4. A gromet comprising a pair of coöperating members each having an opening formed therein, said opening being restricted intermediate its ends, the opening at one side of said restricted portion being larger than at the opposite side; and a neck integral with and projecting from one of said members and adapted for projection in the opening in the coöperating member, and to be clinched over said coöperating member, said neck corresponding in cross section to the contour of said openings, substantially as described.

In testimony whereof I have signed my name to this specification in the presence of two subscribing witnesses.

FREDERICK D. MARTIN.
